(57) **CLAIM**

The ornamental design for a display screen or portion thereof with graphical user interface, as shown and described.

DESCRIPTION

FIG. 1 is a front view of a “display screen or portion thereof with graphical user interface.”

FIG. 2 is another view thereof, depicting an alternative environment;

FIG. 3 is another view thereof, depicting an alternative environment;

FIG. 4 is another view thereof, depicting an alternative environment;

FIG. 5 is another view thereof, depicting an alternative environment;

FIG. 6 is another view thereof, depicting an alternative environment;

FIG. 7 is another view thereof, depicting an alternative environment;

FIG. 8 is another view thereof, depicting an alternative environment;

FIG. 9 is another view thereof, depicting an alternative environment;

FIG. 10 is another view thereof, depicting an alternative environment;

FIG. 11 is another view thereof, depicting an alternative environment;

FIG. 12 is another view thereof, depicting an alternative environment;

FIG. 13 is another view thereof, depicting an alternative environment;

FIG. 14 is another view thereof, depicting an alternative environment;

FIG. 15 is another view thereof, depicting an alternative environment;

FIG. 16 is another view thereof, depicting an alternative environment; and,

(Continued)

FIG. 17 is another view thereof, depicting an alternative environment.

The outermost broken lines show a display screen or portion thereof and form no part of the claimed design. The remaining broken lines, showing portions of the graphical user interface, form no part of the claimed design. The dot pattern in FIGS. 13-16 forms no part of the claimed design.
